Inventor
Elisha P. Kinney.

UNITED STATES PATENT OFFICE.

ELISHA P. KINNEY, OF UNITY, WISCONSIN, ASSIGNOR OF ONE-HALF TO
GEORGE McCURDY, OF SAME PLACE.

CAR-COUPLING.

SPECIFICATION forming part of Letters Patent No. 449,798, dated April 7, 1891.

Application filed November 15, 1890. Serial No. 371,518. (No model.)

To all whom it may concern:

Be it known that I, ELISHA P. KINNEY, a citizen of the United States, residing at Unity, in the county of Marathon and State of Wisconsin, have invented a new and useful Car-Coupling, of which the following is a specification.

This invention has relation to car-couplings, and more particularly to that class thereof known as "pin-lifters."

The object of the invention is to produce improvements upon devices of this same general character heretofore made.

To this end the invention consists of the details of construction, hereinafter more fully described and claimed, and as illustrated in the drawings, in which—

Figure 1 is a perspective view of the end of a car with my improved draw-head attached thereto. Fig. 2 is a central vertical longitudinal section of the draw-head, showing the parts in the act of disengaging the link. Fig. 3 is a section on the line 3 3 of Fig. 1—that is, just below the top plate of the draw-head. Fig. 4 is a transverse section on the line 4 4, Fig. 2.

Referring to the drawings, the letter D designates a draw-head having a flaring mouth M, and through the upper side of the draw-head on a horizontal pivot is mounted a swinging pin P, whose lower end, when in its normal or upright position, engages a recess R in the bottom of the opening in the draw-head. This pin is weighted at its lower end, so that it will normally assume an upright position standing through the link L and holding the same coupled within the draw-head.

Below the top plate of the draw-head slides an operating-plate O, having teeth T along one edge and having a notch N in its front end, which is adapted to straddle the upper end of the pin P when the plate O is moved forwardly, whereby the pin will be rocked upon its pivot and caused to assume a horizontal position, as seen in Fig. 2.

The means for moving and operating the plate O longitudinally within the draw-head may be any that will do the work in the best manner; but I prefer the construction described below.

Mounted in eyes I in the sides of the draw-head, the end of the platform, and the end of the car, if it be a box-car, is a vertical shaft V, having a gear-wheel G keyed thereon at a proper point to engage the teeth T of the plate O.

In Fig. 1 I have represented a box-car in dotted lines and a platform-car in full lines; and this vertical shaft carries a hand-wheel H at a suitable point above the platform, as shown in full lines, or above the top of the box-car, as shown in dotted lines, the idea being that the hand-wheel shall be in a proper position to be operated by a brakeman standing upon the car.

When the link L is driven into the mouth of the draw-head, the pin P is turned upon its pivot and it drops into the link, as will be obvious, the open front end of the notch N permitting this movement. When it is desired to release the link, the hand-wheel H is turned in a proper direction to force the operating-plate O forward and tilt the pin, as shown in Fig. 2, when the link will be released. In this position the inner end of the notch N strikes an angle A upon the rear side of the pin, whereby the plate O is prevented from moving farther forward.

Any suitable means may be provided for preventing the dislocation of the operating-plate at the rear end of the draw-head, which means are preferably removable, in order to allow the plate to be taken out, when desired, for inspection, cleaning, and repair.

What I claim as new is—

1. In a car-coupling, the combination, with a draw-head and a pin pivoted through the upper side thereof and having a weighted lower end, of a plate moving longitudinally within the draw-head in a plane above the pivot of said pin, and means for moving said plate, substantially as described.

2. In a car-coupling, the combination, with a draw-head and a pin pivoted through the upper side thereof and having a weighted lower end, of a plate moving longitudinally within the draw-head in a plane above a pivot of said pin, said plate having a notch in its front end engaging the upper end of the pin and the latter having an angle on its rear

face adapted to strike the bottom of said notch when the plate is moved forwardly, and means for moving said plate, substantially as described.

- 5 3. In a car-coupling, the combination, with a draw-head and a pin pivoted through the upper side thereof and having a weighted lower end, of a plate moving longitudinally within the draw-head in a plane above the 10 pivot of said pin, said plate having a notch in its front end engaging the upper end of the pin and the latter having an angle on its rear face adapted to strike the bottom of said

notch when the plate is moved forwardly, teeth on one edge of said plate, a vertical shaft 15 journaled in eyes in a draw-head and extending above the same and carrying a hand-wheel, and a gear on said shaft engaging said teeth, substantially as hereinbefore described.

In testimony that I claim the foregoing as 20 my own I have hereto affixed my signature in presence of two witnesses.

ELISHA P. KINNEY.
